Fig. A.

7.
fig.

Fig. 8.

Technical drawing of a mechanical assembly labeled "Fig. 8." The drawing shows a central vertical shaft with a diameter of 20. At the top, there is a stepped bearing housing with a bore diameter of 20 and a shoulder diameter of 82. The housing is supported by two bearings. The bottom of the shaft features a stepped collar with a bore diameter of 22 and a shoulder diameter of 20. The overall height of the assembly is 116.

A technical drawing of a mechanical part, labeled 'Fig. 8.' in cursive script. The drawing shows a rectangular base with a central circular hole. A cylindrical component is inserted into this hole, and a rectangular block is attached to the top of the cylinder. The base has several dimensions marked: 29, 32, 21, 21, 21, 46, 21, and 21. The cylinder has a dimension of 29, and the top block has a dimension of 21.

BUTTON INJECTOR AND POSITIONING
ATTACHMENT

Roy E. Fowler, Watkinsville, Ga., assignor of one-half to Luther Henson, Athens, Ga.

Application January 17, 1951, Serial No. 206,467

2 Claims. (Cl. 112—113)

1

This invention relates to attachments for sewing machines and particularly machines for sewing buttons on shirts, trousers, coats and the like, and in particular this invention relates to mechanical instrumentalities for receiving buttons from a chute, turning the button so that openings therein are in registering relation with a needle of a sewing machine and feeding the buttons to a position for receiving the needle of the machine.

The purpose of this invention is to provide mechanical means of feeding and positioning buttons on button sewing machines whereby the necessity of positioning the buttons by hand is eliminated.

Various devices have been provided for feeding buttons and similar objects to sewing and other machines but in the garment making industry considerable time is lost and fingers are damaged because it is necessary to hold a button in position for sewing by hand. With this thought in mind this invention contemplates an attachment having a slide positioned to receive buttons from a chute with means for rotating the buttons to correct positions as they are fed to designated positions on material where they receive the needle of the machine.

The object of this invention is, therefore, to provide a button injecting and positioning attachment for sewing machines in which buttons are positively held and definitely positioned to be attached by stitching to the material of a garment or the like.

Another object of the invention is to provide a button feeding and positioning attachment that may be installed on sewing machines now in use.

A further object of the invention is to provide a button feeding and positioning attachment which turns buttons to correct positions for being attached by stitching to garments which is of a comparatively simple and economical construction.

With these and other objects and advantages in view the invention embodies a slide having a button receiving recess therein with means for rotating a button as the slide is moved forwardly and pins for entering the openings in a button when the button is in a desired position as the button is carried to an attaching position.

Other features and advantages of the invention will appear from the following description taken in connection with the drawings wherein:

Figure 1 is a side elevational view illustrating

2

the position of the attachment on a sewing machine with the needle of the sewing machine shown above a button holding foot of the attachment and with other parts of the sewing machine omitted.

Figure 2 is a plan view of the attachment shown in Fig. 1 showing a button chute extended from one side through which buttons are fed to the slide of the attachment.

10 Figure 3 is a longitudinal section through the attachment showing the parts positioned to receive a button.

Figure 4 is a similar view illustrating the parts in a position where the button is fed from the 15 slide to a positioning foot by which the button is carried to an attaching position on a garment or the like.

Figure 5 is a cross section through the attachment taken on line 5—5 of Fig. 4.

20 Figure 6 is a cross section taken on line 6—6 of Fig. 4 showing the mounting plate of the attachment.

Figure 7 is a plan view showing the button 25 gripping jaws of the button holding foot that carries the button to the attaching position of the attachment said section being taken on line 7—7 of Fig. 4 and shown with the arms of the jaws and slide broken away.

Figure 8 is a cross section taken on line 8—8 30 of Fig. 7, illustrating a button being deposited between the gripping jaws of the positioning foot.

Figure 9 is a cross section taken on line 9—9 35 of Fig. 3 illustrating the mounting plate or bar with a bracket on one side for attaching the device to a bed of a sewing machine.

Figure 10 is a cross section through the slide and mounting bar taken on line 10—10 of Fig. 3.

Figure 11 is a longitudinal section through the 40 intermediate part of the attachment illustrating a tilting cam for withdrawing pins from openings of a button.

Figure 12 is a similar section showing the cam actuated to the pin withdrawing position.

45 Figure 12-A is the cross section taken on line 12—12-A of Fig. 11 illustrating the cam mounting.

Referring now to the drawings wherein like 50 reference characters denote corresponding parts the improved button feeding and positioning attachment of this invention includes a slide 10, channel shaped in cross section, a mounting bar 11, a shaft 12, an elevating lever 13, a cam 14 for withdrawing pins 15 on a spring arm 16 and 55 a button carrying foot 17 having button hold-

ing jaws 18 and 19 carried by a bracket 20 which is resiliently held downwardly by a spring 21.

The slide 10 is provided with a web having flanges with ribs 22 and 23 and the ribs are positioned to travel in grooves 24 and 25, respectively of the mounting bar 11 and the slide is provided with an upper bar 26 that is adjustably attached to the upper surface by bolts 27 and 28 and that is provided with a tongue 29, which is secured to the bar 26 by screws 30 and 31 and that extends from the forward end thereof.

The tongue 29 is positioned to extend over a button, as indicated by the dotted lines 32, in Fig. 2 whereby as a button is received from a chute 33 it is retained in a socket or space 34 provided at the end of the upper bar and between the tongue 29 and upper surface of the slide 10 and in this area the button is positioned over openings 35 and through which the pins 15 on the spring arm 16 extend. The spring arm 16 is attached to the under surface of the upper section of the slide 10 by a screw 36 and with the parts as shown in Figs. 3 and 12 the forward end of the spring arm 16 is held downwardly by the cam 14 whereby the pins 15 extend downwardly 25 from the opening 35, as shown in Fig. 3.

As the slide moves forwardly the sides of a button held in the socket 34 engage a roughened rubber strip 37 at one side and a bar 38 at the other whereby with one side of the button traveling against the smooth surface of the bar 38 and the opposite side frictionally engaging the roughened surface of the rubber strip 37 the button is rotated and as the pins 15 are bearing against the under surface of the button, the spring arm 16 having been released by the cam 14, the beveled upper end of the pins 15 enter the openings of the button when the openings are in registering position with the pins.

The rubber strip 37 is held by a bar 39 with a tongue of the strip positioned in the slot 40 and the bar 39 is secured to the mounting bar 11 by a bolt 41. The bar 38 is also secured by bolts 42 to the mounting bar. The mounting bar 11, as shown in Fig. 9 is also provided with a flange 43 by which the attachment may be mounted in the side of the bed of a sewing machine by a bolt 44, with the bolt extended through hubs 45.

The slide 10 is actuated automatically or by manual means and, as illustrated in Figs. 3 and 4 pressure on the outer end of the shaft 12 moves the shaft inwardly until a set collar 46, thereon engages the end of the slide 10 and thereby moves the slide forwardly. In this movement fingers 47 and 48, between which a pin 49 is positioned actuate the cam 14 through the arms 50 and 51 at the ends thereof and in which the pin 49 is carried whereby the spring arm 16 is released so that the pin 15 may pass upwardly in the openings 35. The fingers 47 and 48 are carried by an arm 52 extended from the end of the shaft 12.

The outer end of the shaft 12 is threaded and an arm 53 is adjustably mounted thereon being held in position by adjusting nuts 54 and 55 and, as illustrated in Fig. 3 the rod 56, on which a spring 57 is mounted is carried by the end of the arm 53 with the opposite end extended through an opening 58 in a support 59 which holds one end of the mounting bar. The rod 56 is provided with set collars 60 and 61, the collar 60 engaging the end of the spring 57 and the collar 61 limiting rearward movement of the rod. The shaft 12 is also provided with a set collar 62 that en-

gages the inner end of a section 63 of the slide 10, also as shown in Fig. 3. After the slide is moved forwardly to deposit a button in the jaws 18 and 19 of the foot 17 the spring 57 returns the slide to the position shown in Fig. 3.

In the forward or feeding movement of the slide a pin 64 engages projections 65 of the lever 13 which is pivotally mounted on a pin 66 in a bracket 67 carried by the end of the support 59 and as the lower end of the lever 13 moves forwardly the upper end travels upwardly forcing the bracket 20 upwardly whereby the foot 17 is moved to the position shown in Fig. 4. The bracket 20 is L-shaped in elevation and a vertically disposed arm 68 thereof is retained in a socket 69 of a block 70 on the bed 71 of the machine and the outer end of the bracket is attached to a section 72 and a foot 17 by bolts 73 and 74. The section 72 is connected to the foot 17 by a downwardly sloping section 75. The spring 21 is mounted on a section 76 of the bed of the machine by a bolt 77.

As illustrated in Fig. 2 the bars 38 and 39 are provided with slotted openings 78 and 79, respectively, so that the positions of the button engaging surfaces may be adjusted to compensate for buttons of different sizes and with the parts arranged in this manner the buttons 32, fed from the chute 33, are received in the socket 34 and by pressing forwardly upon the end of the shaft 12 the slide is moved forwardly whereby the buttons are carried through the blocks 38 and 39 which rotate the buttons until openings 80 in the buttons are in registering relation with the pin 15 carried by the spring arm 16. The slide delivers the buttons to the jaws 18 and 19 of the foot 17 wherein the buttons are gripped by arcuate edges 81 and 82 of the gripping jaws 18 and 19, respectively. With return movement of the slide the foot 17 drops downwardly to the position shown in Fig. 3 where it is upon the material of a shirt or other garment and the needle 83 may be actuated to stitch the button to the garment.

It will be understood that modifications may be made in the design and arrangement of the parts without departing from the spirit of the invention.

What is claimed is:

1. In a button injector and positioner attachment, the combination which comprises an elongated mounting bar having continuous grooves providing tracks in the edges, a slide, channel-shape in cross section having a web with flanges at the sides positioned in the mounting bar and having ribs on the flanges which are positioned to slide in the tracks of the mounting bar, an upper bar carried by the slide, said slide having an open button receiving area positioned beyond the end of said upper bar, the web of said slide having openings therein and said openings positioned in the button receiving area at the end of the upper bar, a spring arm having spaced pins on one end, means mounting the spring arm on the slide whereby the pins are positioned to register with said openings in the web of the slide, means for actuating the spring arm whereby said pins are withdrawn from the openings of the web of the slide, a rubber strip having a rough face mounted in the mounting bar and positioned to be engaged by a button in said button receiving area of the slide for rotating the button in said area as the button is moved forwardly by the slide, means for manually actuating the slide, resilient means urging the slide away

from the button feeding position, a bracket extended over the attachment and adapted to be pivotally mounted on the machine, a foot extended downwardly from the extended end of the bracket and adapted to position a button on a piece of material on the machine, means actuating said bracket for positioning the foot at the discharge end of the slide for receiving a button from the said upper bar thereof, and a button feeding chute extended from one side of the mounting bar.

2. In a button injector and positioner attachment, the combination which comprises an elongated mounting bar having continuous grooves providing tracks in the edges, a slide, channel-shape in cross section having a web with flanges at the sides positioned in the mounting bar and having ribs on the flanges which are positioned to slide in the tracks of the mounting bar, an upper bar carried by the slide, said slide having an open button receiving area positioned beyond the end of said upper bar, the web of said slide having openings therein and said openings positioned in the button receiving area at the end of the upper bar, a spring arm having spaced pins on one end, means mounting the spring arm on the slide whereby the pins are positioned to register with said openings in the web of the slide, means for actuating the spring arm whereby said pins are withdrawn from the openings of the web of the slide, a rubber strip having a rough face
